Richard J. Cook

UNITED STATES PATENT OFFICE.

WILLIAM HENDRY, OF TACOMA, WASHINGTON.

SEAMAN'S NET-NEEDLE.

1,374,503.

Specification of Letters Patent. Patented Apr. 12, 1921.

Application filed May 29, 1920. Serial No. 385,277.

To all whom it may concern:

Be it known that I, WILLIAM HENDRY, a subject of the King of Great Britain, and resident of the city of Tacoma, county of 5 Pierce, and State of Washington, have invented certain new and useful Improvements in Seamen's Net-Needles, of which the following is a specification.

This invention relates to improvements in 10 seamen's needles, and more particularly to improvements in needles especially adapted for use in making or sewing nets; the principal object of the invention being to provide a needle which will greatly facilitate 15 the work for which it is intended, which may be more easily threaded than are needles now generally in use for doing like work, and which is of such construction that it is applicable to a special type of machine 20 used for winding thread onto the carrying members within the needle body.

In accomplishing this and other objects 25 of the invention, I have provided the improved details of construction, the preferred forms of which are illustrated in the accompanying drawings, wherein—

Figure 1 is a longitudinal edge view of a needle constructed according to the present invention.

30 Fig. 2 is a side view of the same.

Fig. 3 is a transverse section on the line 3—3 of Fig. 1.

Fig. 4 is a detail view of the thread holding member.

35 Referring more in detail to the several views of the drawings, wherein like reference numerals designate like parts: 1 and 2 designate the opposite face plates which form the body of the needle and which are 40 of an elongated character provided with gradually tapering, pointed forward ends 3 and rounded rearward ends 4.

The main body portions of these plates are held substantially parallel in a certain 45 spaced apart relation by two intermediate posts 5 and 6, but forwardly of the post 6 the tapered ends of the pointed portions 3 are drawn gradually together. The plates, rearwardly of the post 5 are curved slightly 50 inward but do not come together, rather they leave a substantial opening between their ends. The longitudinal edges of the plates are also curved toward each other,

giving the needle a somewhat round shape, which makes it convenient and easy to 55 handle.

Fixed to the post 5 and extending toward the post 6 so as not to be in the way of threads being wound within the needle, is a 60 plate 8 provided with a tapered slot 9, whereinto the end of a thread or cord may be placed and drawn inwardly to hold it while being wound in the needle.

In using the device, the thread or cord to 65 be used therewith is extended between the plates 1 and 2 and drawn into the wedge slot 9 so that it is securely held. The thread is then wound about the posts 5 and 6 until there is a substantial supply within the 70 needle. This winding is preferably done by an automatic winding machine of the character disclosed in Patent No. 1,216,994 granted to me on shuttle winder, which includes means for holding the pointed ends 75 of the needle plates apart while the device is revolved and thread fed thereonto.

In use, the needle is handled as the ordinary seaman's needle in sewing or weaving nets, but has been found to be more easily 80 handled, easier to wind a supply of thread thereon, and of a type that will be relatively inexpensive.

What I claim as new, is:

1. A needle of the character described 85 comprising two elongated, opposite face plates, posts intermediate said plates rigidly spacing the same apart in substantial parallel relation, said plates being tapered to a point and drawn together at their forward 90 ends, and spaced apart at their rearward ends, and a thread holding plate fixed to one of said posts having a tapered slot therein for holding one end of a thread that may be wound about said posts. 95

2. In a device of the character described, the combination with opposite face plates and posts fixed intermediate corresponding ends of said plates to hold the same rigidly spaced, of a thread holding plate fixed to 100 one of said posts and extending toward the opposite post, and having a tapered slot therein, for the purpose set forth.

Signed at Tacoma, Washington, this 22d day of May, 1920.

WILLIAM HENDRY.
